UNITED STATES PATENT OFFICE

MAX GARBELL, OF CHICAGO, ILLINOIS, ASSIGNOR TO VICTOR ADDING MACHINE COMPANY, OF CHICAGO, ILLINOIS, A CORPORATION OF ILLINOIS

DEMOUNTABLE HINGE AND FASTENER FOR COVERS OR LIDS

Application filed November 9, 1925. Serial No. 68,041.

This invention relates to carrying devices or cases for typewriting machines, but has particular relation to means for demountably hinging and fastening the covers thereof to their bases, and it consists in certain peculiarities of the construction, novel arrangement and combination of the various parts thereof as will be hereinafter more fully set forth and specifically claimed.

10 The principal object of the invention is to provide a very simple and inexpensive device to be used on the covers and bases on which bases typewriting machines may be mounted for securely holding said parts together, but 15 which will permit them to be readily detached, so that the machine of each device, may be exposed and be immediately made ready for use.

Various other objects and advantages of 20 the invention will be disclosed in the following description and explanation, which will be readily understood when read in conjunction with the accompanying drawing in which—

25 Fig. 1, is an enlarged vertical sectional view of a portion of the base and a part of the cover of a carrying case for a typewriting machine, illustrating one of the fasteners mounted thereon and with its parts in the positions they will occupy when the parts of 30 the case are fastened together.

Fig. 2, is a view in elevation of the rear wall of the casing, showing it fore-shortened for the convenience of illustration, and equipped 35 with my improvements.

Figs. 3 to 5, inclusive, are detached perspective views of details of the invention.

Similar numerals of reference designate like parts throughout the different views of 40 the drawing.

Referring now to the drawings, the reference numeral 6 designates the inverted box-like portion of a carrying case for typewriters which portion has its lower end open 45 in which the base 7 of the case snugly fits. Upon this base 7 may be mounted in the usual or any preferred way a typewriting machine (not shown) for which the function of the case is to support and carry such a machine.

50 To the rear end of the lower surface of the base 7, is secured in spaced relation to one another a pair of angle brackets, designated as a whole, by the numeral 8, each of which consists of a base portion 9, and an upright part 10. The upright portion of each of the 55 brackets is provided with a vertically disposed slot 11, each of which extends from near the upper surface of the base 7, to a suitable point near the upper end of the upright part 10 in which it is located.

It will be understood that these angle brackets 8 are permanently fixed to the base 7 of the case and in such a way that they as well as the base can be freely inserted between the front and rear end walls of the 65 case.

The rear end wall 12 of the box-like part of the case 6 is provided in its lower end or portion with a pair of vertical slots 13 which are spaced from each other in parallelism and so as to coincide with the slots 11 of said angle brackets. However, it will be observed by reference to Figs. 1 and 2 of the drawing that the slots 13 open at their lower ends through the lower end of the wall 12, which 75 wall has secured to its lower outside portion a pair of angle brackets 14, each of which has a base flange 15 normally lying in the same plane with the bases 9 of the angle brackets 8, that is, beneath the lower edge of the wall 12 of the box-like part of the case. The upright portion of each of these brackets 14 is secured to the wall 12 so as to cover the slots 13 therein. Thus it will be understood that the flange 15 of each of the brackets 14 80 will rest under the lower edge of said wall. At the middle of each flange 15, is punched out of or otherwise formed and secured thereto a holding member for an upright forked spring catch, designated as a whole by the 85 numeral 16, each of which consists of an upright arm 17 having at its upper end a forward extension 18 and its lower end provided with an opening 19 to receive said holding member, which is designated by the reference 90 numeral 20 and which holding member, in the present instance, consists of a projection 21 struck out of and turned upwardly and then longitudinally in a horizontal plane 95 with respect to its flange 15, upon the hori-

zontal portion of which the opening 19 of the member 16 is fitted. Each of the flanges 15 also has, in the present instance, struck up from its middle portion a projection 22, the upper portion of which lies at the free end 70 of the part 21 and serves to hold the member 16 in position.

The lower portion of the arm 17 terminates in a flat straight line as at 23, see Fig. 4, and 10 rests against that portion of each of the flanges 15 from which the projection 22 is struck up. Just rearwardly of each of the openings 19 in the arms 17 is provided a rounded portion 24 from which is upwardly 15 extended a spring member 25 which latter contacts at its upper end with the inner surface of one of the brackets 14 directly rearwardly of the extensions 18 which normally project through the slots 13 and each of 20 which said extensions is provided on its front surface with a downwardly and outwardly inclined part 18' as shown in Figs. 1 and 4 of the drawings for the purpose of co-acting with the upper end of each of the brackets 10 25 to force the catch members 16 rearwardly when the box-like part 6 of the casing is being placed downwardly over the base. During this operation it is apparent that the spring members 25 will yield sufficiently 30 to permit the members 16 being deflected outwardly after which they will press said members forwardly thus causing them to pass through the slots 11 so as to engage the upper ends of said slots and thereby prevent the 35 raising of the box-like member of the casing.

From the foregoing and by reference to the drawings, it will be clearly understood and readily seen, that, assuming the cover or box-like part 6 to be in its fastened position 40 as shown in Fig. 1 of the drawing, it is obvious, that by slightly tilting the front part of the cover rearwardly, the arms 16 will be caused to be released from the slots 11 and the front ends of the extensions 18 to contact 45 with the brackets 8 just above the slots 11 therein. In this position of the parts, it is evident that the cover can now be removed from the base and the machine mounted thereon. The operation of fastening the cover to 50 the base has been before explained, and it is deemed unnecessary to herein repeat said explanation.

Having thus fully described my invention, what I claim as new and desire to secure by 55 Letters Patent is—

1. In a device of the class described, the combination of the base of a carrying case with a pair of spaced brackets vertically extended from one edge thereof and each having 60 a vertically disposed slot, an inverted box-like cover adapted to receive at its lower portion said base and provided in one of its walls with a pair of vertical slots to coincide in part with said slots in the brackets, another pair of brackets secured to the cover 65

over the last named slots and each having a flange at its lower end provided with a holding member, and a bifurcated spring catch mounted on each of said holding members and extended vertically in said coinciding slots. 70

2. In a device of the class described, the combination of a carrying case base, a cover therefor, and disengageable means for releasably fastening the base and cover together, said means comprising a slotted member on said base, and a spring catch member on said cover having a portion thereof locatable in the slot of said slotted member when said cover and base are in closed relation, said catch and slotted member being so associative that said catch may be rotated out of engagement with said slotted member upon disengagement of said cover and base. 75

3. In a device of the class described, the combination of a carrying case base, a cover therefor, and disengageable means for releasably fastening the base and cover together, said means comprising a slotted member on said base, and a bifurcated spring catch member comprising an engaging prong and a biasing prong, said engageable prong being locatable in the slot of said slotted member when said cover and base are in closed relation, said catch and slotted member being so associated that the engageable prong may be rotated out of engagement with said slotted member upon disengagement of said cover and base. 80

4. In a device of the class described, the combination of a carrying case base, a cover therefor, and disengageable means for releasably fastening the base and cover together, said means comprising a slotted member on said base, a bifurcated spring catch member comprising an engageable prong and a biasing prong, and a bracket member secured to said cover and upon which said spring catch is so mounted that said biasing prong functions to force said engaging prong into the slot in said slotted member when said cover and base are in closed relation, said members being so associated that said engageable prong may be rotated out of engagement with said slotted member to release 100 said cover from said base. 105

5. In a device of the class described, the combination with a carrying case base and an inverted box-like cover adapted to receive and close said base, of securing means comprising a bracket secured to one edge of said base and having a vertically disposed slot above said base, and a spring catch member for engaging a portion of said base bracket, said cover being provided with an opening 110 in which said catch is receivable so that the major portion of the operating parts of said catch are contained within said cover opening. 115

6. In a device of the class described, the 120
